(57) **CLAIM**

The ornamental design for a T-shaped padlock shackle, as shown and described.

DESCRIPTION

FIG. 1 is a perspective view of a T-shaped padlock shackle showing my new design;

FIG. 2 is a top plan view thereof;

FIG. 3 is a right side elevation view thereof, the left side being a mirror image; and,

FIG. 4 is a front elevation view thereof, the rear view being a mirror image.

The broken lines showing a padlock body represents unclaimed subject matter and forms no part of the claimed design.
